Specification for Design.

Patented Sept. 6, 1910.

Application filed July 2, 1910. Serial No. 570,207. Term of patent 3½ years.

To all whom it may concern:

Be it known that I, SIDNEY O. BIGNEY, a citizen of the United States, residing at Attleboro, in the county of Bristol and State of Massachusetts, have invented a certain new, original, and ornamental Design for a Locket and Vinaigrette, of which the following is a specification.

In the accompanying drawings which form a part of this specification, Figure 1 is a front elevation of a locket and vinaigrette embodying my design, and Fig. 2, a side elevation of the same.

I claim:

The ornamental design for a locket and vinaigrette, as shown.

SIDNEY O. BIGNEY.
